UNITED STATES PATENT OFFICE.

MORGAN W. BROWN, OF NEW YORK, N. Y.

IMPROVEMENT IN COMPOSITION-STOPPERS FOR VESSELS.

Specification forming part of Letters Patent No. 121,152, dated November 21, 1871; antedated November 9, 1871.

To all whom it may concern:

Be it known that I, MORRAN W. BROWN, of the city, county, and State of New York, have invented a new and Improved Composition-Stopper for Vessels; and I do hereby declare the following to be a full, clear, and exact description thereof, which will enable those skilled in the art to make and use the same.

This invention relates to a chemically-prepared stopper, which is intended particularly for vessels containing volatile liquids, such as spirits of turpentine, naphtha, or other hydrocarbons or ethers, but which can be used for vessels of any desired description and containing liquids or gases of any kind, with the exception of a few acids.

My stopper is prepared of a composition of glycerine, gelatine, and an alkali, which are mixed together in about the proportion of thirty parts of glycerine, forty parts of gelatine, and four parts of an alkaline solution of 10° Baumé. From this mixture stoppers of the required size are formed by means of suitable molds, or the mixture may be rolled out in sheets of suitable thickness and the stopper punched out therefrom in the same manner as cork stoppers are now made. In some cases I take an ordinary cork stopper of the required size and coat it with my composition by dipping it therein or otherwise; but in this case the proportions of the in-

gredients must be somewhat changed, so as to produce a liquid in which the cork stoppers can be dipped. In some cases the composition may be made without the alkali, or instead of the alkali some other salt may be used.

By either of these processes a stopper is obtained which is impermeable to volatile liquids, such as naphtha, benzine, spirits of turpentine, sulphuric ether, chloroform, and which, when inserted into a glass bottle, closes the mouth thereof hermetically, so that the ground-glass stoppers now used for closing bottles containing volatile liquids can be dispensed with. My stoppers can, however, also be used for casks or barrels; and they can be produced very cheap, so that they are within the reach of the general public.

What I claim as new, and desire to secure by Letters Patent, is—

1. A chemically-prepared stopper, made of glycerine and glue mixed with or without an alkali, substantially as described.
2. A cork stopper coated with a composition of glycerine and glue, mixed with or without an alkali, substantially as set forth.

MORGAN W. BROWN.
